Specification of Letters Patent. Patented Apr. 19, 1921.

Application filed May 28, 1918. Serial No. 237,009.

To all whom it may concern:

Be it known that I, GEORGE C. CUMMINGS, a subject of the King of Great Britain, residing at East Orange, in the county of 5 Essex, State of New Jersey, have invented certain new and useful Improvements in Telegraph Systems, of which the following is a full, clear, concise, and exact description.

10 This invention relates to telegraph systems and more particularly to systems for the simultaneous transmission of a plurality of messages over one and the same line circuit.

15 The principal object of this invention is to provide a system wherein superimposed alternating current and direct current telegraphic working may be carried on over the conductors of a telephone circuit or circuits.

20 In accordance with the present invention there is provided an improved arrangement of direct current duplex equipments and alternating current equipments combined to render independent telegraphic service over 25 circuits or the conductor of one or more electrically balanced telephone line pairs.

This invention is illustrated diagrammatically in the accompanying drawing, in which for the sake of clearness, only so much 30 of a telegraphic and telephonic equipment has been shown as will be necessary to a clear understanding of the system.

Figure 1 of the drawing shows a combined direct current and alternating current 35 telegraphic equipment suitable for use in the simultaneous transmission and reception of messages routed over one line conductor with an earth return circuit, such line conductor serving as one side of a metallic telephone circuit. Fig. 2 shows an alternate arrangement of a combined direct current and alternating current equipment for rendering the same service as that possible with the equipment shown in the first figure. In 40 Fig. 3 of the drawing, there are shown direct current duplex telegraphic equipments arranged to be operated in earth return relation from each conductor of a telephone line pair, while an arrangement for superimposing alternating current telegraph 45 working is connected to operate in metallic circuit relation over the two line leads of the same telephone pair. In Fig. 4 there is shown a current amplifying and current filtering arrangement suitable for use with the 50 alternating current telegraphic equipment

shown in the first three figures of the drawing. In Fig. 5 is shown a plan arrangement for applying the present system to communication service over two telephone line 60 pairs; in this figure there is also shown an equipment for controlling the operation of telephone call signals over the commonly employed line conductors.

In describing this invention, a line lead 65 1 (Fig. 1) is connected to a direct current duplex equipment formed of a receiving relay 5, ratio arms 6 and 7, and an artificial line AL. A transmitting branch is formed through a differentially connected 70 impedance unit 9 and a transmitting key 10, which controls the inclusion of oppositely poled line batteries 11 and 12 with the line lead. As well understood in the art, incoming direct current impulses over 75 the line lead 1 may disturb the balance of this duplex equipment in such a manner that the armature of the relay 5 will be reciprocated in step with the reversals of the incoming impulses and in phase therewith establish connections from its correspondingly poled contact stops with a conductor 8, which may be understood as extending to a reading sounder or other suitable telegraphic receiving device (not 80 shown). The conventional plus and minus signs at the contact stops of the relay 5 will be understood to indicate that these stops are connected with correspondingly poled 85 source of grounded current. In transmitting message impulses by means of direct currents, the key 10 may be operated to connect the batteries 11 and 12 alternately through the impedance coil 9 to the apex or neutral point intermediate the bridge 90 arm resistances 6 and 7. As well understood in the art, such impulses, although neutralized in the relay 5, nevertheless, become effective over the line lead 1 to operate a receiving relay at a remote station. For convenience, it may be assumed that an equipment identical to the equipment shown in 95 the drawing is present at an assumed distant station.

In describing the operations by which alternating currents may be employed for the transmission and reception of messages over the line lead 1 at the same time that messages may be under transmission by the direct current method already described, a 100 generator 15 of alternating currents, preferably of sine wave form, is connected from 105

earth to a telegraph key 17. Depression of the key 17 first effects closing of its contacts 19, following which its contacts 18 are separated for purposes as will presently be described. During the time the key is in such operated position, a current path may be traced from the generator 15, by way of a resistance unit 16, the key contacts 19 and one winding 21 of a current transformer 20, to earth. The alternating currents through the winding 21, induce corresponding currents in a second winding 22 of this transformer. These induced currents may complete a circuit from an earth connection, thence by way of two branching circuits, the first of which may be traced through a winding 26 of a second transformer 25, a condenser 29, thence by way of the artificial line AL, to earth. The second path from the transformer 20 may be traced through a second winding 27 of the transformer 25 and a condenser 30, to the line lead 1. Since the two alternating current circuits just traced are arranged to form a symmetrical balance with respect to the direct current duplex equipment, these alternating currents are non-effective with respect to the direct current relay 5, although they may traverse the line lead 1 as described and cause the operation of suitable receiving devices at the distant station. A third winding 28 of the transformer 25 is connected to the current amplifying and filtering system shown in Fig. 4 but the connective relation of the transformer coils 26 and 27 is differential, one coil with the other, as relates to the transmitted alternating currents just described. Therefore, these currents are non-effective with the third winding 28, and the receiving devices are therefore not affected by alternating currents transmitted from this station.

For the reception of alternating current impulses incoming over the line lead 1, the major portion of such alternating currents may traverse the condenser 30 (Fig. 1), the winding 27 of the transformer 25 and the winding 22 of the transformer 20, to earth. A portion of the incoming currents also traverses the winding 26 of the transformer 25, the condenser 29 and the artificial line AL to earth. From the winding 27 and partially from the winding 26, corresponding current changes are induced in the winding 28 of the transformer 25, and, turning to Fig. 4 of the drawing, since the winding of an amplifier control magnet 35 is connected from the terminals of the latter winding, this magnet will correspondingly work a microphone pile which may be in the form of a telephone transmitter button. For convenience of description, the transformer 25 of Fig. 1 has also been included with the receiving equipment shown in Fig. 4. In response to vibratory or alternating currents

as received, this magnet will operate the microphone at a frequency corresponding with the frequency of the alternating currents, which it will be understood is relatively high. In this manner the associated battery acts on a transformer 37 to in turn operate a second similar amplifier comprising coil 38 and button 39 to induce currents in a filtering network comprising transformers 41 and 42 and associated condensers. After passing through this filtering network the amplified currents work a polarized relay 43 to interrupt a normally closed circuit through a relay 44. The latter relay thereupon disconnects the winding of a polar relay 45 from a source of positive current and connects it to respond to a source of negative current, thereby disconnecting a telegraphic receiving device 46 which, for convenience, has been shown as a reading sounder. In this manner, the device 46 responds respectively to the presence and cessation of alternating current signals originating at a distance station.

The employment of current amplifiers as described in connection with the reception of alternating currents permits the use of relatively weak or attenuated currents of this character, particularly with respect to their strength in the line portion of the circuits. Such low wattage condition affords additional margin relative to the telephone, telephone call-signal and direct current telegraphic equipments not being affected by these alternating currents. In turn the current filtering equipment described, comprises such tuned or electrical time constant relation of circuits that current surges or extraneous electrical effects are screened out and prevented from reaching the devices on which the alternating current telegraphic signals are reproduced.

Referring to the contacts 18 of the key 17, during the time messages are being received over the alternating current equipment these contacts establish a closed loop circuit which includes the winding 21 of the transformer 20 and a resistance unit 23. With respect to incoming impulses from the line lead 1 as routed through the winding 22 of the transformer 20, the closed circuit through the winding 21 of this transformer provides a closed secondary therefor, and thereby improves the condition of the circuits for the reception of the alternating current signals. It will, of course, be clear, as already described, that in sending by means of the key 17, the contacts 18 disconnect this closed loop circuit during the time alternating currents from the generator 15 are active through the transformer winding 21; this betters the circuit conditions in the matter of alternating current signals transmitted by the key 17.

A condenser 13 connected from a point

intermediate the impedance coil 9 and the apex of the duplex equipment to earth is for the purpose of absorbing current surges which may otherwise interfere with the 5 duplex equipment.

Referring to Fig. 2 of the drawing, the direct current portions of the circuits shown in this arrangement are substantially the same as those shown in the first figure. The 10 alternating current portion of the equipment, however, differs in certain respects from the alternating current arrangement already described. It will be noted that from the winding 22 of the transformer 20, 15 one branch circuit extends through the winding 27 of the transformer 25, thence through an adjustable resistance 31 and a variable condenser 32, to earth, while the other branch extends through the winding 26 of 20 the transformer 25, thence branching over two paths, one of which continues by way of the condenser 29 and the artificial line AL to earth, while the second path extends over the condenser 30 to the line lead 1. By 25 means of the adjustable resistance 31 and the variable condenser 32, alternating currents transmitted by the key 17 as already described, may be rendered non-effective in the winding 28 of the transformer 26, due 30 to equalizing differential current action through the windings 26 and 27 of the transformer 25. Therefore transmitted alternating currents established in sending by means of the key 17 are non-effective in 35 the winding 28 and receiving equipment connected thereto which may be the same as the equipment shown and already described in connection with Fig. 4 of the drawing. For the reception of alternating current 40 signals, such currents from the lead 1 traverse the condenser 30 and the winding 26 of the transformer 25, thence by way of the winding 22 of the transformer 20, to earth. Such currents through the winding 26 set 45 up corresponding currents in the winding 28 of the transformer 25 to operate the receiving devices in a manner corresponding with that already described.

In other respects the operation of the 50 equipment shown in Fig. 2 corresponds substantially with the operation of the equipment shown and described in connection with the first figure of the drawing.

Referring to Fig. 3 of the drawing, two 55 line conductors 60 and 61 forming a metallic circuit respectively terminate in telegraphic duplex equipments A and B, and are also provided with composite telephone equipment C. In this arrangement duplex equipments A and B correspond with the direct current equipments shown in the first figures of the drawing. For the alternating current working, however, one set of telegraphic equipment has been dispensed with and the 60 other alternating current equipment arranged 65 for operating in metallic circuit relation over the two line conductors 60 and 61. Since the direct current portion of the telegraphic equipment operates from the earth over the line conductors in the same manner as that 70 already considered, no description thereof will be necessary in connection with the arrangement shown in this figure of the drawing. Therefore, description of the alternating current equipment will be proceeded 75 with. In the transmission of signals from this point, the key 17 controls the inclusion of energy from the alternating current generator 15, through the winding 21 of the transformer 20, thereby setting up corresponding 80 current changes in the winding 22 of this transformer, the terminals of which are connected through a local loop circuit which extends through the winding 27 of the transformer 25, the variable condenser 85 32, the adjustable resistance 31 and a second variable condenser 33. From one terminal of the winding 22, a branch circuit extends through the winding 26 of the transformer 25, thence branching over one path formed 90 by the condenser 29 and the artificial line AL, to earth, and a second path formed through the condenser 30 and impedance unit 63 to the line conductor 61, lead 2. These currents reach the distant station and 95 after passing through associated circuits at that point, reach the opposite line conductor 60 and return over an impedance unit 62, the lead 1, thence by way of the condenser 30 at the equipment A to a derived connection which reaches the opposite terminal of the winding 22 of the transformer 20. The connective relation of the windings 26 and 27 of the transformer 25 being differential, one with the other, the variable condensers 100 32 and 33 and the adjustable resistance 31 may be so proportioned that the strength of the transmitted alternating currents, traversing the winding 27, may in effect be equal to that portion of the alternating currents 105 which traverse the winding 26 of this transformer. Therefore, such currents will not affect the winding 28 which may be connected to control receiving equipment similar to that already described in connection 110 with Fig. 4 of the drawing.

In receiving alternating current signals from the distant station, the impulses may be traced from the line conductor 60, impedance coil 62, lead 1, the condenser 30 115 (at A), winding 22 of the transformer 20, the winding 26 of the transformer 25, the condenser 30 (at B), line 2, impedance coil 63, thence returning to the distant station over the line conductor 61. These currents through the winding 26 of the transformer 25 set up corresponding current changes in the winding 28 of this transformer to 120 operate receiving devices as already described in connection with Fig. 4 of the 125 130

drawing. In all other respects the operation of the equipment shown in Fig. 3 corresponds substantially with the operation of the equipment described in connection with the first and second figures of the drawing. The artificial line or network comprising the condensers 32 and 33 and the resistance 31 has, for convenience of description, been shown in elemental form; it will be understood, however, that in practice this network may be considerably elaborated upon with respect to additional equipment which may include inductance as well understood in the art.

It will, of course, be obvious that some portion of the alternating currents may be traced over the bridge arms 6 and 7, condenser 13 or perhaps incidentally over other paths formed in the general assembly of the equipment as shown. The proportion of the various capacities, resistances, etc., however, provides that such losses will be non-effective and relatively negligible, the working circuits being in accordance with those transmitting and receiving circuits which were definitely traced.

Referring to the telephone portion of the equipments, reference will first be made to Fig. 3 of the drawing. In tracing the circuits of the telephone equipment, a path for telephonic currents extends from the line conductor 60 by way of a condenser 64, the winding 65 of an inductance coil 66, thence by way of a second condenser 68 to the opposite line conductor 61. From the terminals of a second winding 67 of the induction coil 66, telephone equipment may be connected for communicating in metallic circuit relation over the line conductors 60 and 61. It will be understood that a conductor 69 connected at a central point on the winding 65 of the induction coil 66 may represent one side of a so-called "phantom" telephone circuit. One side of this circuit may operate in simplex or differential relation over the two line conductors 60 and 61, while the other side for this phantom circuit may be routed over a second telephone pair (not shown) in a manner similar to that in which the first lead of the phantom circuit is connected over the present line circuit pair. The condensers 70 and 71 and impedance coils 72 and 73 as connected form a series parallel with the winding 65 of the induction or repeating coil 66 and a ground connection present intermediate the coils 72 and 73 further serves the purpose of absorbing or equalizing the current effects with respect to the telephone equipment, while the condensers 74 and 75 respectively connected from each of the telegraph leads 1 and 2 to earth also serve in maintaining a suitable balance of the circuits and in preventing other than telephonic currents reaching the telephone equipments.

Referring to Fig. 5 of the drawing, this plan arrangement provides that a symmetrically balanced telephone circuit "A," formed of conductors 51 and 52, and a second similar circuit "B," formed of conductors 53 and 54, may be equipped with telegraphic devices similar to those shown and described in connection with Figs. 1 and 2 of the drawing and in addition thereto, these circuits may be provided with equipment for carrying on several different telephonic communications as over the transformer 66 for the lines A and B respectively, and by way of the leads 69 and 79 for phantom service over the metallic circuits. In connection with the circuit "A" there are shown equipments suitable for rendering service in the operation of call signals necessary, as well understood, in connection with the telephone service.

In initiating a telephone call signal by way of the jack 91 of the circuit "A," it will be understood that equipment, not shown, but included with this jack is provided for applying an alternating current of relatively low frequency, as, say, approximately 16 cycles per second to the contact members 92 and 93 of this jack. Such connection with the jack 91 separates its normal contacts to disconnect a signal receiving device 94 which, for convenience, is shown in the form of a "drop." The low frequency alternating current traverses the contacts 86 of the relay 90 and conductor 85, thence by way of a condenser 100 and the windings of a polarized relay 101 to the conductor 95, thence returning over the contacts 87 of the relay 90 to the opposite side of the connection at the jack 91. The armature of the relay 101 is so arranged that its contacts 102 and 103 are normally opened. Under the action of alternating currents through this relay, its armature will be reciprocated in phase therewith to alternately close the contacts 102 and 103. At the instant that the contacts 102 close, a source of grounded battery 104 will be connected through the contacts 102 and associated resistances with a bus conductor 105. From this bus conductor, the circuit divides over one path formed through an alternating current relay 106 and a battery 107 to earth and over another path which includes the winding of a second alternating current relay 108 and a battery 109 to earth. While the battery 104 is connected in differential relation with respect to the batteries 107 and 109, the potential of the battery 104 is greater than the potential of the batteries 107 and 109. Ordinarily, a relation in which the potential of the battery 104 is twice the potential of each of the other batteries, has been found to give satisfactory results at the instant the contacts 102 may be closed. It will, therefore, be clear that current will flow from the battery 104 through the relay 106 and the battery 107 to earth.

104 over the circuits traced through each of the alternating current relays 106 and 108. Current in an opposite direction will flow from the batteries 107 and 109 through the 5 respective alternating current relays during instants the contacts 103 of the relay 101 may be closed. In this manner, it will be clear that alternating currents will be active through the relays 106 and 108 during the 10 time that alternating currents may be applied by way of the jack 91, as described, and it will further be clear that the frequency of the alternating currents through these relays will be in phase with the alternating currents applied at the jack. The relay 106 is of such design or adjustment that it will not be affected by the low frequency alternating currents, the relay 108, however, being so proportioned or adjusted 15 as to readily respond to the low frequency described. Operation of the relay 108 completes a circuit from a source of current 120 through the winding of a relay 110 to earth. Operation of the relay 110 completes circuit 20 from a battery 120 which extends through the windings of a relay 111 and the relay 80 to earth. Relay 111 thereby operated completes a circuit which includes an alternating current generator 112 through a winding 25 114 of transformer 113 and operation of the relay 80 causes separation of its contacts 81 and 82 to disconnect the conductors 85 and 95 and in closing its contacts 83 and 30 84 connects a secondary winding 115 of the transformer 113 in a closed loop circuit which includes a winding 67 of the transformer 66. The frequency of the current produced by the generator 112 is relatively 35 high, say, approximately 133 cycles per second, and such currents may traverse the line conductors 1 and 2 of the metallic circuit "A" to reach a distant station and there operate a telephone call signal which may be typical of the signal 94 shown at the present 40 station.

In describing operations whereby a telephone call signal originating at a distant station may be received at the present station, let it be assumed that at the distant 45 point operations are carried out in a manner similar to that just described in connection with the sending out of high frequency signaling currents from the present equipment. Such incoming alternating currents 50 act through the transformer 66 to complete circuit over the contacts 81 and 82 of the relay 80, thence by way of the conductors 85 and 95 through the condenser 100 and relay 101. The relay 101 is so constructed 55 or adjusted that it may readily respond to alternating currents of either low or high frequency; therefore, in responding to the high frequency currents the contacts 102 and 60 103 of this relay are alternately closed in 65 phase therewith to establish alternating cur-

rents of a corresponding frequency through the operating circuits already traced through the relays 106 and 108. In this case, the low frequency relay 108 will continue inert while the high frequency relay 106 will close 70 its contacts to complete a circuit from a battery 116 to operate a relay 117. The operation of the latter relay connects the battery 116 to operate the relay 90, and separation of the contacts 86 and 87 of the latter relay 75 disconnects the conductors 85 and 95 from the jack 91, while closure of the contacts 88 and 89 of this relay connects a low frequency generator 118 to act over the normal contacts of the jack 91 in operating the "drop" 80 signal 94, it being understood, of course, that no connection would be present in the jack 91 during the time it will be necessary to send a call signal, as described, from a distant station.

From the foregoing description it will be clear that by means of the present invention, a plurality of direct current channels and alternating current channels may be employed for the transmission of telegraphic 90 messages during the time that one or more telephonic conversations may be under way on the same line conductors and further, that signaling operations may be carried out on a telephone channel without interference 95 with either the alternating current or the direct current telegraphic channels or with the other telephonic channels.

Although the present arrangement represents a preferred embodiment for carrying out the features of this invention, it will be understood that various changes in the organization of the apparatus may be made without departing from the spirit of this 100 invention.

What is claimed is:

1. In a system of simultaneous telephony and telegraphy, a circuit formed of a pair of line conductors, means for telephoning over said circuit, duplex equipments for 110 employing direct currents in signaling in earth-return relation over said line conductors respectively, and further equipment for each line conductor comprising a first transformer having several windings, a plurality of derived circuits opaque to direct currents extending from said respective duplex equipment to respective windings on said transformer, a second transformer connected to extend the derived circuits 115 120 through said first transformer, and means included with said second transformer for employing alternating currents in telegraphing over said line conductors respectively independently of said telephoning 125 and said direct current telegraphing.

2. In a telegraph system, a line circuit, means for employing direct currents in telegraphing over said line, means for employing alternating currents in telegraphing 130

over said line, two polar relays capable of responding in phase with the alternations of said alternating currents, and a relay not capable of responding in phase with said alternations controlled by one of said polar relays and controlling the other polar relay for the reception of said alternating currents.

3. In a telegraph system, a line circuit, 10 means for the transmission of signals over said line by means of alternating currents, a first relay responsive to each alternation of said currents, a second relay not capable of operating at a speed equal to the frequency of said alternations controlled by said first relay, a third relay identical to said first relay controlled by said second relay, and telegraphic receiving means controlled by said third relay.

20 4. In a system of simultaneous telephony and telegraphy, a plurality of circuits each formed of a pair of line conductors, means for telephoning over each of said circuits and for telephoning in phantom relation 25 over said plurality of circuits, means for the control of telephone call-signals over each of said circuits and over said phantom circuit, earth-return equipment for each conductor of said circuits comprising duplex equipment for telegraphing by means 30 of direct currents, equipment for telegraphing by means of alternating currents over said line circuits, and a network comprising current amplifiers and current filters employed in the reception of said alternating currents.

5. In a telegraph system, a line circuit, equipment for the employment of direct currents in telegraphing over said line, a 40 first transformer having several windings, condensers connected to form a plurality of derived circuits extending from different points on said direct current equipment to respective windings on said transformer, a second transformer connected to complete said derived circuits, a source of alternating currents, transmitting means to include said source of currents with said second transformer in signaling over said line, impulse 45 receiving means, and means included with said first transformer to render said receiving means responsive to alternating currents from said line but unresponsive to currents controlled by said transmitter.

55 6. In a telegraph system, a line conductor, duplex equipment including a real and an artificial line for the transmission and reception of signals by means of direct currents, a transformer having several windings, a condenser connected to form a derived circuit extending from said real line to a winding of said transformer, a second condenser connected to form a derived circuit extending from said artificial line to a 60 second winding of said transformer, a sec-

ond transformer, one winding of said second transformer connected to extend said connections through the first and second windings of said first transformer, a source of alternating currents, transmitting means 70 for connecting said source of alternating currents through a second winding of the second transformer in the transmission of signals to said line circuit, impulse receiving means, a third winding on said first 75 transformer non-responsive to said transmitted alternating currents included with said receiving means, and means controlled by said transmitting means for substituting a closed loop connection on the second winding of said second transformer during intervals of cessation of current from said source of alternating currents.

7. In a telegraph system, a line circuit, duplex equipment including a real line, an 85 artificial line and devices for the transmission and reception of signals by means of direct currents, a first transformer having several windings, a plurality of condensers, a derived circuit extending from said line circuit including a condenser and one winding of said first transformer, a second derived circuit extending from said artificial line including a condenser and another winding of said first transformer, a second transformer, a first winding of said second transformer connected to jointly extend the circuit of the two windings of the first transformer to earth, signal receiving means, a third winding for said first transformer for rendering 90 alternating currents from said line effective with said signal receiving means, transmitting means, a second winding for said second transformer controlled by said transmitting means, and means controlled by said transmitting means for establishing a closed loop connection for said second winding of the second transformer during periods signals may be under reception by said receiving means.

8. In a telegraph system, duplex equipment including a real line, an artificial line and devices for the transmission and reception of signals conveyed by means of direct currents, a first transformer, a condenser 115 connected in a first branch circuit extending from said real line through a first winding of said transformer, a condenser connected in a second circuit branching from the artificial line and merging with said first branch 120 circuit, a second transformer, a first winding for said second transformer, connected to extend the circuit of the first winding of said first transformer to earth, a second artificial line opaque to direct currents, a derived circuit connected intermediate the first windings on said first and second transformers which includes a second winding of said first transformer and said second artificial line, a source of alternating currents, means for 125 130

- including said source of currents with a second winding on said second transformer to effect signaling over the real line, means for the reception of alternating current signals, a third winding on said first transformer for said receiving means, and adjustable means in said second artificial line for conditioning said first transformer to render said transmitted currents non-effective with 5 said alternating current receiving means.
9. In a telegraph system, a first and a second line conductor, duplex equipment including an artificial line and devices for the transmission and reception of signals by 10 means of direct currents for each of said line conductors, a first and a second transformer included intermediate the duplex equipment of each of said line conductors, receiving means included with said first transformer, 15 means included with said second transformer for the transmission of alternating currents serially over said first and second line conductors, a network including capacity and resistance connected between said 20 transformers, and means for employing telephones in communicating over said first and second line conductors.
10. In a telegraph system, a plurality of line conductors, duplex equipment comprising an artificial line and devices for the reception and transmission of impulses by 25 means of direct currents in ground relation over each of said line conductors, a first transformer, a second transformer, a network comprising capacity and resistance to 30 form a plurality of paths intermediate the duplex equipments of said line conductors, means controlled by said first transformer for the reception of alternating current impulses, a source of alternating currents, transmitting means for rendering said alternating currents effective through said second transformer with said plurality of line conductors, means for employing telephones 35 in communicating over said line conductors, and means controlled by said network for rendering said first transformer effective to 40 neutralize the effect of alternating currents controlled by said transmitter with respect 45 to said alternating current receiving means.
- 50
11. In a telegraph system, a first equipment comprising a first and a second line conductor, duplex equipment including an artificial line and devices for the reception 55 and transmission of direct current signaling impulses in earth return relation over each of said line conductors, a derived circuit including two condensers extending from each of said line conductors to the associated artificial line, a first and a second transformer 60 bridged at a point intermediate said condensers in joining the equipment of said first and second line conductors, alternating current receiving means included with said first
- transformer, a network comprising capacity and resistance included with said first transformer and the derived circuit point intermediate said condensers of the equipment of the second line conductor, a source of alternating currents, means for rendering said alternating currents effective with said second transformer in signaling in series over said first and second line conductors, means for telephoning over said line conductors, a second equipment typical of the first equipment described, and means for providing additional telephone communications by way of the conductors common to the first and the second equipments.
12. In a communication system, a metallic line circuit, means for employing direct currents for telegraphing in ground relation over each conductor of said metallic circuit, means for employing telephones in communicating over said metallic circuit independently of said direct current telegraphing, means for employing alternating currents in telegraphing in ground relation over each conductor of said metallic circuit independently of said telephoning and said direct current telegraphing, means for the reception of said alternating current telegraph signals comprising a first polar relay and a second polar relay, and a neutral relay intermediate said polar relays for establishing 95 reversals of current polarity in controlling said second-mentioned polar relay.
13. In a system of composite telegraphy and telephony, a metallic line circuit formed of two electrically balanced conductors, means for providing a telephone channel for communicating over said metallic circuit, call signals for use in connection with said telephone channel, means for applying alternating currents over said metallic circuit in 100 controlling said call signals, means for employing direct currents for telegraphing in earth return relation over each conductor of said metallic line circuit independently of said telephone communication channel and 105 said call signal control, means for employing alternating currents in telegraphing in earth return relation over each conductor of said metallic circuit independently of said telephone channel, said call signal control 110 and said direct current telegraphing, a first polar relay for the reception of alternating current impulses, a second relay normally energized through said first relay, a third relay of polarized type, normally disabled 115 telegraph receiving means, and means controlled by said second relay for rendering said third relay effective to energize said receiving means during periods alternating currents may be present in said first relay.
